UNITED STATES PATENT OFFICE

GORDON W. RUSSELL, OF BROOKLINE, MASSACHUSETTS, ASSIGNOR TO JAMES RUSSELL
BOILER WORKS CO., A CORPORATION OF MASSACHUSETTS

FIRE-TUBE STEAM BOILER

Application filed March 15, 1928. Serial No. 261,784.

This invention relates to steam boilers of the fire tube type such as are commonly used for heating houses and public buildings.

In boiler practice in this particular field especially there has long existed a serious difficulty in providing a satisfactory installation of a heating system where the head room, that is, the available space between floor and ceiling of the boiler room, is insufficient to provide an adequate differential or head between the first floor radiator and the water line of a boiler having sufficient capacity to adequately heat the building. Too limited a head or elevation of the radiators above the water line of the boiler involves a backing up of the water into the radiator intakes, thus clogging circulation of steam with consequent insufficiency of heat and inefficient burning of fuel.

In such situations it has been customary to resort to a circulating force pump which not only adds to the cost of the system and to the expense of operation but is not entirely satisfactory.

To remedy this trouble, I have devised a new construction of boiler which, without impairing the boiler capacity, provides a boiler construction that permits a very substantial head room between the water line and the radiator intakes but without impairing its capacity, while at the same time increasing its efficiency as compared with the old circular type of horizontal fire tube boiler.

In general, the invention comprises a boiler of substantial elliptical shape in cross section, with major axis of the ellipse extended horizontally across the boiler, while the short axis is in a vertical plane, the top and bottom walls of the boiler being secured together at suitable intervals to impart the necessary strength or resistance to pressure.

In the accompanying drawings I have illustrated the features of construction embodying the principles of this invention, in which

Fig. 1 is a longitudinal central vertical section of a boiler embodying this improvement.

Fig. 2 is a front elevation, partly in cross

section through the fire box illustrating the same construction.

Fig. 3 is a diagrammatic view illustrating the difference in water line and consequent difference in head between my construction of boiler and a prior art circular boiler of equal capacity.

In the accompanying drawings the boiler shell 1 is of elliptical shape in cross section and is provided rearwardly of the fire box 2 with a series of fire tubes 3 extending into a vertical passage at the rear end of the shell so as to allow the combustion gases to return through the return fire tube 4 to the offtake stack 5 of the boiler.

The crown sheet 6 has a correspondingly flat curvature and, at its sides is continued down as at 6^a to form a water leg on each side of the fire box.

To adequately sustain the top and bottom walls of the boiler shell against pressure, a series of vertical stay-rods 8 are securely anchored to these walls, while the forward portion of the boiler above the fire box has a series of shorter stay-rods 9 tightly connecting the crown sheet with the overhead wall of the boiler.

It has been deemed unnecessary to illustrate other details of construction which correspond to well known boiler practice.

Fig. 3 illustrates the large gain in head room or distance between the water line and radiator intakes that is derived from an adoption of my construction. The circular dotted line with its downward vertical continuations shows the outline of a boiler having the same capacity as the outline of boiler shown in full lines in said figure, following the practice embodying my invention.

In a boiler of eighty horse power capacity, there will be an actual gain in head room of about fifteen inches, assuming the two types of boiler to be set on the same base or floor level. Moreover, the elliptical principle, involving as it does the relatively wide and vertically short series of fire tubes, gives the fire more direct access to the interior of the fire tubes which makes for further efficiency in the generation of steam.

What I claim is:

A fire tube boiler embracing in its construction a boiler shell of elliptical cross section with the major axis of the ellipse extending horizontally, a fire box located at the lower forward end of the shell and partitioned at its top from the overhead semi-elliptical upper half of the boiler shell by an upwardly arched crown sheet, a series of fire tubes extending directly from the rear of the fire box to the rear end portion of the boiler, a series of return tubes arranged above the level of the crown sheet and extending the whole length of the boiler, and vertical stay rods passing between both sets of fire tubes and tieing the top and bottom walls of the ellipse to resist the pressure of the internal body of steam.

In witness whereof, I have subscribed the above specification.

GORDON W. RUSSELL.
